(57) **CLAIM**

The ornamental design for a back panel for a light emitting tile, as shown and described.

DESCRIPTION

FIG. 1 is a top view of a back panel for a light emitting tile according to the present disclosure.

FIG. 2 is an isometric view thereof; and,

FIG. 3 is another isometric view thereof.

The broken lines shown are included for the purpose of illustrating environmental structure and form no part of the claimed design.
